UNITED STATES PATENT OFFICE.

FRANK VERDIN, OF HAMILTON, OHIO.

COMBINED SHADE-BRACKET AND CURTAIN-POLE SUPPORT.

No. 866,093.

Specification of Letters Patent.

Patented Sept. 17, 1907.

Application filed March 30, 1907. Serial No. 365,581.

To all whom it may concern:

Be it known that I, FRANK VERDIN, a citizen of the United States, residing at Hamilton, in the county of Butler and State of Ohio, have invented certain new 5 and useful Improvements in a Combined Shade-Bracket and Curtain-Pole Support, of which the following is a specification.

This invention is a combined shade-bracket and curtain-pole support and has for its object a fixture of 10 this kind which can be easily put up, and has a wide range of adjustment.

In the accompanying drawing, Figure 1 is a front elevation of the invention and Fig. 2 is a vertical section on the line 2—2 of Fig. 1.

15 Referring specifically to the drawing, 5 denotes a plate having a longitudinal slot 6. At the top and bottom of the plate are rearwardly presented parallel flanges 7 and 8, respectively. At the extremity of the top flange is an upstanding flange 9 having longitudinal 20 slots 10 to receive screws or other fastening means, 11 whereby the device is secured to the window casing. To one end of the flange 9 is riveted or otherwise secured a forwardly presented arm 12 having a seat 13 for the curtain-pole. The flanges 7 and 8 form a track in 25 which a bracket-carrying slide is mounted. The slide comprises a plate 14 engaging the face of the plate 5, and having top and bottom flanges 15 and 16, respectively, engaging over the flanges 7 and 8, respectively. The slide is held at adjustment on the track by a bolt 17 30 passing through the slot 6 and through a hole in the plate 14. On one end of the bolt is a head 18 and on the other end is screwed a wing-nut 19. Upon loosening the nut the slide can be adjusted lengthwise on the track and it will be firmly held in adjusted position 35 when the nut is tightened. The flange 16 has a depending stem 20 which carries a shade-bracket member 21. Said member comprises a plate which projects forwardly from the stem 20 and has the usual open-

ing 22 to receive the end of the shade-roller spindle. At the opposite side of the window casing will be located a fixture similar to the one herein described for supporting the other end of the shade-roller spindle. 40

The construction herein described enables the bracket-supporting device to be adjusted lengthwise on the window casing upon loosening the screws 11, 45 and the bracket-carrying slide can also be adjusted lengthwise on the track of the supporting device. This double adjusting feature enables the curtain-pole support to be arranged to suit the length of the pole after which the bracket-carrying slide can be ad- 50 justed on the track according to the length of the shade-bracket. A wide range of adjustment is therefore had and the parts can be readily arranged to suit different lengths of shade-rollers and curtain-poles.

Another important feature is the manner in which 55 the bracket-carrying slide is supported on the track, the object being to give a firm support to the bracket. It will be noted that by the engagement of the flanges 15 and 16 with the flanges 7 and 8 the weight of the shade-roller will be borne by the track, and no strain 60 is placed on the clamping-bolt 17, which therefore serves only to hold the parts at adjustment thus rendering it less liable to get loose.

I claim:—

In a shade bracket, a support comprising a channelled 65 plate placed horizontally with its edges toward the window casing and having a flange at the upper rear edge fastened to the casing, and a U-shaped slide fitting upon and around said plate and adjustably fastened thereto, the slide having a shade bracket depending from its lower 70 rear edge, adjacent to the casing.

In testimony whereof I affix my signature, in presence of two witnesses.

FRANK VERDIN.
